[57] CLAIM

The ornamental design for a seat cushion, as shown and described.

DESCRIPTION

FIG. 1 is a plan view of a seat cushion, shown from the top and showing my new design;

FIG. 2 is a bottom plan view thereof;

FIG. 3 is a right side elevational view thereof, the opposite left side being a mirror image;

FIG. 4 is a front elevational view thereof, the opposite rear view being a mirror image;

FIG. 5 is a cross-sectional view thereof taken about line 5—5 of FIG. 1;

FIG. 6 is a cross-sectional view thereof taken about line 6—6 of FIG. 2; and,

FIG. 7 is a perspective view thereof.
